TELEPHONE SYSTEM WITH TWO-PARTY LINES

Harald Valdemar Alexandersson and Erik Valdemar Hullegård, Stockholm, Sweden, assignors to Telefonaktiebolaget L. M. Ericsson, Stockholm, Sweden

Application February 18, 1938, Serial No. 191,330
In Sweden November 26, 1936

8 Claims. (Cl. 179—33)

The invention relates to telephone systems having two-party lines, i. e., party lines serving each two subscribers' telephones, and particularly to such systems having local battery feed. 5 In order that systems of the kind referred to shall function satisfactorily, the following requirements must be met.

The calls must be secret while maintaining the possibility of making internal calls. In the 10 exchange each subscriber should have his own calling equipment, and it should be possible to provide for individual metering of calls, if desired. It should be possible to use ordinary magneto ringers connected by means of two-wire 15 lines to a junction equipment. Through the present invention there has been provided for the first time a system which meets all of said requirements and which, in addition, is simple in operation and can be used also with lines having 20 a comparatively great leakage.

The invention will now be described more in detail with reference to the accompanying drawings, in which Figure 1 shows a first embodiment of the invention, and Figure 2 a second embodiment.

Referring to Figure 1, two subscribers' telephones A and B are connected each by means of a two-wire circuit *a* or *b* respectively to a junction equipment comprising two relays A₁ and B₁ 30 and two condensers C₃ and C₄. The junction equipment is connected by means of a two-wire junction line L_a, L_b to the exchange in which individual jacks JA, JB are allotted to the two subscribers A and B.

35 The relay A₁ in the junction equipment controls a contact 1 over which one branch of the circuit *a* of the subscriber A can be connected to the outgoing line L_a and also a shifting contact 2 over which the other branch of the circuit *a* can be connected alternatively to earth and to the branch L_b of the outgoing line. When 40 said branch is connected to earth, a signalling circuit is closed through the subscriber's telephone, and a contact 5 controlled by the relay B₁, over the line L_a to a signalling device S₁ provided in the exchange, said device being connected at its other terminal to earth. The relay A₁ also controls a contact 3 which is included in the signalling circuit of the subscriber B. In

45 similar manner the relay B₁ controls the contacts 4, 5 and 6. Both relays are slow-acting in order not to be actuated by the ringing signals sent out. The line equipment in the exchange consists of two relays A₂ and B₂, one 50 for each subscriber, two condensers C₁ and C₂,

and a balancing resistance 9. Said relays are connected in parallel each with a rectifier RA or RB respectively whereby said relays are slow-acting, this being necessary in order that the ringing current sent out shall not interfere with the proper operation of the relay. To each subscriber there is also allotted a calling equipment in the form of a drop indicator S₁ or S₂ respectively and a jack JA or JB.

5 When the subscriber A, by turning his magneto ringer, makes a call the current from the ringer passes from earth over the contact 2, the contact 5, the condenser C₃ and the line wire L_a to earth at the drop indicator S₁. When 10 on energization the latter is released a circuit is closed over a contact of the indicator, said circuit extending from the minus pole of the battery and through the relay A₂, the line wire L_a and the relay A₁ to earth. The relays A₁ and A₂ are then energized, the relay A₁ connecting the subscriber A over the contacts 1 and 2 to the line L_a, L_b. At the same time the relay A₁ interrupts at its contact 3 the signalling circuit of the subscriber B, preventing said circuits from making a call. The relay A₂ interrupts 15 its contacts 6 and 7, thereby disconnecting the drop indicators S₁ and S₂. The relay A₂ also closes a contact 8 thereby connecting a balancing resistance 9, which is earthed at one end, to the line branch L_b over the contact 12. In 20 corresponding manner the relay B₂ controls the contacts 10 and 11 and also the just mentioned contact 12, said contact being opened on operation of the relay B₂ thereby preventing the 25 balancing resistance 9 from being connected to any one of the line wires L_a, L_b while a conversation is being carried on between the two subscribers A and B. The operator thereafter 30 answers the call in ordinary manner by inserting the answering plug into the jack JA. When, 35 after conversation has been finished, the releasing signal indicator drops and the operator takes down the connecting cord, the relays A₁ and A₂ will be deenergized.

A call from the subscriber B is put through in 40 similar manner. The calling signal will then be received at the drop indicator S₂.

In case the operator wants to set up a connection to a party line subscriber, for example, the subscriber A, she has only to insert the plug 45 into the jack JA, both relays A₁ and B₁ being then energized, whereafter a ringing signal can be transmitted to the subscriber A in ordinary manner.

An internal talking connection, for example, 50

from the subscriber A to the subscriber B, is set up in ordinary manner with the exception that the operator should take down the answering cord while sending the ringing signal to prevent the subscriber A from hearing the ringing signal, and the telephone of the subscriber A from being connected in shunt to the telephone of the subscriber B.

In the modified embodiment according to Figure 2 the relays A1 and B1 are each connected in parallel with a rectifier 20 or 23 and connected in series with a winding 21 or 25, each of said windings being connected in parallel with an appertaining rectifier 22 or 24 respectively, said rectifiers being turned in a direction opposite to the direction of the rectifier 20 or 23 respectively. The balancing resistance consists of a winding 26 connected in parallel with a rectifier 27, said winding being connected at one end to the positive pole of a battery the middle point of which is earthed. On a call from, for example, the subscriber A, current will pass from earth in the junction equipment through the rectifier 22 the winding of the relay A1, the line wire La, the relay A2 and to minus pole at the drop indicator S1. At the same time current will pass in the opposite direction over the wire Lb from the plus pole of the battery, through the balancing winding 26, the contact 8 in its upper position, the contact 12, the wire Lb, the rectifier 23 (the latter thus shunting the relay B1) and the winding 25 to earth. After completed talking connection there are thus connected to the wire La the relays A1 and A2, and to the wire Lb the relay B1 and the balancing winding 26, all of said apparatus being passed by current and all being made as relay windings, wherefore the line becomes very well balanced. The last described connection can therefore be used to advantage in lines in which disturbances occur.

We claim:

1. In a telephone system, a common line, a junction equipment connected to one end of said common line, two subscriber lines branched from said junction equipment, said junction equipment comprising a relay for each subscriber, said relays each being connected at one terminal to an appertaining branch of the common line and at its other terminal to earth, a signalling circuit for each subscriber extending over earth and an appertaining branch of the common line, said junction equipment comprising further for each subscriber one set of contacts, each set consisting of two contacts over which the appertaining subscriber's line can be connected to the common line, and a third contact included in the signalling circuit of the subscriber and a fourth contact included in the signalling circuit of the other subscriber, said relays each being adapted to control an appertaining set of contacts.

2. In a telephone system, a common line, connected in one end to an exchange, a junction equipment, connected to the other end of said common line, two subscriber lines branched from said junction equipment, said junction equipment comprising a relay for each subscriber, said relays each being connected at one terminal to an appertaining branch of the common line and at its other terminal to earth, a signalling circuit for each subscriber extending over earth and an appertaining branch of the common line, said junction equipment comprising further for each subscriber one set of contacts, each set consisting of two contacts over which the appertaining

subscriber's line can be connected to the common line, and a third contact included in the signalling circuit of the subscriber and a fourth contact included in the signalling circuit of the other subscriber, said relays each being adapted to control an appertaining set of contacts, and both being further adapted to be energized from the exchange during internal calls.

3. In a telephone system, a common line, a junction equipment connected to one end of said common line, two subscriber lines branched from said junction equipment, said junction equipment comprising a slow-acting relay for each subscriber, said relays each being connected at one terminal to an appertaining branch of the common line and at its other terminal to earth, a signalling circuit for each subscriber extending over earth and an appertaining branch of the common line, said junction equipment comprising further for each subscriber one set of contacts, each set consisting of two contacts over which the appertaining subscriber's line can be connected to the common line, and a third contact included in the signalling circuit of the subscriber and a fourth contact included in the signalling circuit of the other subscriber, said relays each being adapted to control an appertaining set of contacts.

4. In a telephone system, a common line, connected in one end to an exchange, a junction equipment, connected to the other end of said common line, two subscriber lines branched from said junction equipment, said junction equipment comprising a relay for each subscriber, said relays each being connected at one terminal to an appertaining branch of the common line and at its other terminal to earth, a signalling circuit for each subscriber extending over earth and an appertaining branch of the common line, said junction equipment comprising further for each subscriber one set of contacts, each set consisting of two contacts over which the appertaining subscriber's line can be connected to the common line, and a third contact included in the signalling circuit of the subscriber and a fourth contact included in the signalling circuit of the other subscriber, said relays each being adapted to control an appertaining set of contacts.

5. In a telephone system, a common line connected in one end to an exchange, a junction equipment connected to the other end of said common line, two subscriber lines branched from said junction equipment, said junction equipment comprising a relay for each subscriber, said relays each being connected at one terminal to an appertaining branch of the common line and at its other terminal to earth, a signalling circuit for each subscriber extending over earth and an appertaining branch of the common line, said junction equipment comprising further for each subscriber one set of contacts, each set consisting of two contacts over which the appertaining subscriber's line can be connected to the common line, and a third contact included in the signalling circuit of the subscriber and a fourth contact included in the signalling circuit of the other subscriber, said relays each being adapted to control an appertaining set of contacts.

6. In a telephone system, a common line connected in one end to an exchange, a junction equipment connected to the other end of said common line, two subscriber lines branched from said junction equipment, said junction equipment comprising a relay for each subscriber, said relays each being connected at one terminal to an appertaining branch of the common line and at its other terminal to earth, and being adapted to be energized from the exchange in a circuit extending over earth and one line branch, a signalling circuit for each subscriber extending over earth and an appertaining branch of the common line, said junction equipment comprising further for each subscriber one set of contacts, each set consisting of two contacts over which the appertaining subscriber's line can be connected to the common line, and a third contact included in the signalling circuit of the subscriber and a fourth contact included in the signalling circuit of the other subscriber, said relays each being adapted to control an appertaining set of contacts.

each being adapted to control an appertaining set of contacts, a further relay for each line branch and a balancing resistance earthed at one end which are disposed in said exchange, said 5 energizing circuits for the junction relays each comprising one of said further relay disposed in the exchange, last mentioned relays each being adapted to control a contact by means of which said balancing resistance is connected to the 10 branch of the line to which said last mentioned relay is not connected.

6. In a telephone system, a common line connected in one end to an exchange, a junction equipment connected to the other end of said 15 common line, two subscriber lines branched from said junction equipment, said junction equipment comprising a relay for each subscriber, said relays each being connected at one terminal to an appertaining branch of the common line and at 20 its other terminal to earth, and being adapted to be energized from the exchange in a circuit extending over earth and one line branch, a signalling circuit for each subscriber extending over earth and an appertaining branch of the common 25 line, said junction equipment comprising further for each subscriber one set of contacts, each set consisting of two contacts over which the appertaining subscriber's line can be connected to the common line, and a third contact included 30 in the signalling circuit of the subscriber and a fourth contact included in the signalling circuit for the other subscriber, said relays each being adapted to control an appertaining set of contacts, a further relay for each line branch and a 35 balancing resistance earthed at one end which are disposed in said exchange, said energizing circuits for the junction relays each comprising one of said further relay disposed in the exchange, last mentioned relays each being adapted to control 40 a contact by means of which said balancing resistance is connected to the branch of the line to which said last mentioned relay is not connected, one of said further relays also being adapted to control a contact which on internal 45 calls disconnects said balancing resistance.

7. In a telephone system, a common line connected in one end to an exchange, a junction equipment connected to the other end of said common line, two subscriber lines branched from 50 said junction equipment, said junction equipment comprising a relay for each subscriber, said relays each being connected at one terminal to an appertaining branch of the common line and at its other terminal to earth, and being adapted to be energized from the exchange in a circuit 55 extending over earth and one line branch, a signalling circuit for each subscriber, extending over earth and an appertaining branch of the common line, said junction equipment comprising further 60 for each subscriber one set of contacts, each set consisting of two contacts over which the appertaining subscriber's line can be connected to the

common line, and a third contact included in the signalling circuit of the subscriber and a fourth contact included in the signalling circuit for the other subscriber, said relays each being adapted to control an appertaining set of contacts, a further relay for each line branch and a balancing resistance earthed at one end which are disposed in the exchange, said further relays being made slow-acting by being connected in parallel each with a rectifier, said energizing circuits for 10 the junction relays each comprising one of said further relay disposed in the exchange, last mentioned relays each being adapted to control a contact by means of which said balancing resistance is connected to the branch of the line 15 to which said last mentioned relay is not connected.

8. In a telephone system, a common line connected in one end to an exchange, a junction equipment connected to the other end of said 20 common line, two subscriber lines branched from said junction equipment, said junction equipment comprising a relay for each subscriber, said relays each being connected at one terminal to an appertaining branch of the common line and 25 at its other terminal to earth and being connected in parallel with a rectifier and in series with a winding which is connected in parallel with a rectifier turned in a direction which is opposite to the direction of the first mentioned one, 30 each of said relays being further adapted to be energized from the exchange in a circuit extending over earth and an appertaining line branch, a signalling circuit for each subscriber, extending over earth and an appertaining branch of the 35 common line, said junction equipment comprising further for each subscriber one set of contacts, each set consisting of two contacts over which the appertaining subscriber's line can be connected to the common line, and a third contact 40 included in the signalling circuit of the subscriber and a fourth contact included in the signalling circuit for the other subscriber, said relays each being adapted to control an appertaining set of contacts, a further relay for each line branch 45 and a balancing resistance earthed at one end which are disposed in the exchange, said further relays being made slow-acting by being connected in parallel each with a rectifier, said balancing resistance consisting of a winding which is 50 connected in parallel with the rectifier and is connected at one terminal to the positive pole of a battery the middle point of which is earthed, said energizing circuits for the junction relays comprising each one of said further relay disposed 55 in the exchange, last mentioned relays each being adapted to control a contact by means of which said balancing resistance is connected to the branch of the line to which said last mentioned relay is not connected.
